UNITED STATES PATENT OFFICE.

CHARLES F. BENNEKE, OF CHICAGO, ILLINOIS.

GOLF-BALL TEE.

Application filed December 29, 1924. Serial No. 758,509.

This invention relates to improvements in golf ball tees.

One object of the invention is to provide a simple and efficient portable device adapted to replace the usual sand tee for supporting a golf ball, which may be economically manufactured.

Another object of the invention is to provide golf ball supports of the character described, adapted to be stuck into the ground, which may be conveniently carried in large numbers by the player to be used wherever desired.

Still another object of the invention is to provide a golf ball support made of relatively soft, pliable material which will readily yield or bend when accidentally struck by the golf club during play, so that there will be no interference with the stroke of the player, and which may be easily re-formed or bent back into its original shape so that the same may be used repeatedly.

A further object of the invention is to provide a support of the character indicated, composed of material which lends itself readily to cutting and shearing, whereby when the golf ball support is either accidentally or intentionally left on the green, it will form no obstacle during mowing the green, inasmuch as the same will offer very little resistance to the cutting operation of the blades of the mower.

More specifically, the object of my invention is to provide a one-piece golf tee made of sheet material, including a substantially horizontally disposed supporting member and a prong extending downwardly therefrom, adapted to be fixed in the ground to hold the tee in upright position, the supporting member being formed to accommodate a restricted zone of the golf ball to support and hold the same.

Other objects and advantages of the invention will more fully and clearly appear from the description and claims hereinafter following.

In the drawing, forming a part of this specification, Figure 1 is a side elevational view showing my improved device in operative position, the golf ball being indicated in dotted lines. Figure 2 is an enlarged, vertical, sectional view corresponding substantially to the line 2—2 of Figure 1. Figure 3 is an enlarged top plan view of the tee shown in Figure 1. Figure 4 illustrates the blank form which the golf tee is formed.

And Figure 5 is a view similar to Figure 1 on an enlarged scale, showing a different embodiment of the invention.

Referring first to the embodiment of the invention illustrated in Figures 1 to 4, inclusive, 10 indicates the body portion of my improved supporting device, having a prong or anchoring pin 11 formed integral therewith. The body portion 10 is in the form of a relatively thin cup-shaped member adapted to receive a restricted zone at the bottom of the golf ball to support the same. The concavity of the cup-shaped member is preferably formed so as to correspond to the spherical surface of the golf ball, although the same may be formed of a curvature of either greater or lesser diameter than the ball. The prong 11 is disposed centrally of the cup-shaped member and is in the form of an elongated, flat blade, the side edges 12 of which taper toward the lower end of the same. The bottom end 13 is preferably rounded. As clearly shown in Figures 1 to 4, inclusive, the prong 11 and the body portion 10 are formed from a single blank of thin sheet material. As most clearly shown in Figure 4, the blank is in the form of a disk-like member 14 having a lateral projection 15 tapered toward the outer end and forming a part of the prong. The disk proper is slit inwardly from the outer edges along lines 16—16 forming continuations of the side edges of the projection 15. The prong member 11 is formed by bending the material along a line connecting the inner ends of the slits 16, thereby disposing the prong in a position centrally of the disk.

Figure 1 illustrates the device in operative position, the prong 11 being shown inserted in the ground so that the cupped body portion 10 is disposed in substantially horizontal position, thereby acting as a retaining member, to support the ball in proper position for play.

My improved golf tee may be formed of any suitable cheap material which is relatively soft and pliable and may be easily cut or sheared, such as fiber, sheet aluminum, zinc, or any other suitable metal. I preferably form the support of thin sheet aluminum, because the same is not corrosive and therefore will not soil the pockets of the garment in which it is carried. It will be evident that any number of these devices may be carried by the player and inserted in

the green at the desired place. It will also be evident that the same support may be moved from place to place and used repeatedly. Should the support be left in the green, either accidentally or intentionally, it will not be an objectionable obstacle to the operation of mowing the green, inasmuch as the same is readily shearable, the cutting blades of the mower easily severing the same.

The method of forming my improved golf tee is as follows: The blank shown in Figure 4 is die cut from a thin, flat sheet so as to form the disk portion 14 and the prong 15. The slits 16 are then formed and the prong 15 bent at right angles to the disk as hereinbefore described. The disk portion is then subjected to a die shaping operation to cup the same as shown in Figure 2. It will be evident that due to the cupping operation, the diameter of the outer periphery of the body portion will be shortened, thereby contracting the mouth of the opening 17 from which the upper end of the prong is formed, as clearly shown in Figure 3. The prong 15 is preferably made of such a width that the mouth of the opening 17 will be substantially closed when the cupping operation has been completed, thereby providing a continuous outer edge 18 which embraces the supported zone of the golf ball.

In using my improved golf tee, the same is inserted in the ground, as shown in Figure 1, and the ball supported on the cupped body member 10. If the tee is accidentally struck by the club during play, the same will readily yield, due to the pliable nature of the material of which it is composed. When the tee has thus been distorted or bent out of shape, it may be manually reformed or bent back into its original state by the player without the use of tools.

The embodiment of the invention illustrated in Figure 5 comprises a cup-shaped member 19 and a prong or anchoring pin 20 projecting downwardly therefrom similar to the cup-shaped member 10 and prong 11 of the embodiment illustrated in Figures 1 to 4, inclusive. The prong 20 has the side edges thereof indented, thereby forming spaced projections 21-21, which serve to more securely anchor the support when inserted in the ground. In all other respects the device illustrated in Figure 5 is similar to that shown in Figures 1 to 4, inclusive, and is formed by the same method.

From the preceding description, it will be evident that I have provided an exceedingly simple support for a golf ball, to manufacture which requires a minimum of machine operations and consequently may be very economically and cheaply produced.

While I have herein shown and described what I now consider the preferred manner

of carrying out my invention, the same is merely illustrative, and I contemplate all changes and modifications that come within the scope of the claims appended hereto.

I claim:

1. A one-piece support made from flat sheet material, comprising a ball-holding element and a prong of flat sheet metal formed integrally with said ball holding element and extending centrally therefrom, said prong being adapted to be inserted in the ground to anchor the support in fixed, upright position. 75

2. In a method of forming a support for a ball; forming from a sheet of material a disk-like member having a projecting portion; slitting said disk inwardly along lines forming continuations of the outer edges of said projecting portion to form with said projecting portion an elongated prong attached to the disk inwardly of the edge thereof; bending said prong at an angle to said disk; and forming said disk into cup shape. 80 85

3. In a method of making a ball support; forming from a thin sheet of material a ball retaining member having a prong-like portion extending therefrom slitting said member inwardly of its limits to provide a prolongation of said prong; and bending said prong-like portion at an angle to said retaining member. 90 95

4. A support for a ball, including a body portion and an integral prong separated from the body portion and extending centrally therefrom and at an angle to the said body portion. 100

5. A support for a ball, including a body portion and a prong formed integrally, said prong being separated from said body portion inwardly of the limits thereof, and being angularly disposed with reference thereto. 105

6. A support including a body member having a portion cut out to provide a prong extending at an angle to said body member, said body member being shaped so as to restrict the opening formed in cutting out said prong. 110

7. A support including a body member having a portion cut out to provide a prong extending at an angle to said body member, said body member being shaped in a manner to restrict the opening formed in cutting out said prong, the cut out portions being of such dimensions that shaping of said body portion to effect juxtaposition of the cut out portions remote from said prong provides a ball support of predetermined size. 115 120

In witness that I claim the foregoing I have hereunto subscribed my name this 24th day of December 1924.

CHARLES F. BENNEKE.
